(57) **CLAIM**

The ornamental design for a computing device case bezel, as shown and described.

DESCRIPTION

FIG. 1 is a front perspective view of a first computing device case bezel.

FIG. 2 is a front view of the first computing device case bezel of FIG. 1.

FIG. 3 is a left side view of the first computing device case bezel of FIG. 1.

FIG. 4 is a right side view of the first computing device case bezel of FIG. 1.

FIG. 5 is a bottom view of the first computing device case bezel of FIG. 1.

FIG. 6 is a top view of the first computing device case bezel of FIG. 1.

FIG. 7 is a front perspective view of a third computing device case bezel.

FIG. 8 is a front view of the third computing device case bezel of FIG. 7.

FIG. 9 is a left side view of the third computing device case bezel of FIG. 7.

FIG. 10 is a right side view of the third computing device case bezel of FIG. 7.

FIG. 11 is top view of the third computing device case bezel of FIG. 7; and,

FIG. 12 is a bottom view of the third computing device case bezel of FIG. 7.

In FIGS. 1-12, all broken lines to the front of the solid line seam of the computing device case bezel depict portions of the article that form no part of the claimed design. The

(Continued)

remaining broken lines, showing a computing device behind the bezel in FIGS. 1, 3-7 and 9-12, represent an environment and form no part of the claimed design. All unshaded surfaces between the solid lines and broken lines form no part of the claimed design.

1 Claim, 12 Drawing Sheets
